GAUGE FOR COLD HEADERS AND THE LIKE

William L. Clouse, Tiffin, Ohio, assignor to The
National Machinery Company, Tiffin, OhioApplication November 10, 1930
Serial No. 494,789

7 Claims. (Cl. 10—11)

This invention relates to a gauge for use with heading machines wherein stock in the form of a wire or rod is fed into the machine where a blank is cut-off and then positioned for shaping by the 5 fixed and movable dies.

It has always been desirable to use a gauge for limiting the movement of the stock into the machines, but, because of the designs of the headers it has been the practice heretofore to support the 10 gauge at a point remote from its point of contact with the abutting stock. Such gauges have not been satisfactory, however, because they have yielded under the pressure of the stock fed thereagainst and as a result the severed blanks have 15 not always been of proper length.

The slides of heading machines are always provided with liner plates and it is an object of the present invention to support the gauge from one of these plates so that it will be more rigid 20 and better able to withstand pressure from stock than should it be supported at the side of the bed or body of the machine which is remote from the stock.

With the foregoing and other objects in view 25 which will appear as the description proceeds, the invention resides in the combination and arrangement of parts and in the details of construction hereinafter described and claimed, it being understood that changes in the precise embodiment of the invention may be made within the scope of what is claimed without departing from the spirit 30 of the invention.

In the accompanying drawing the preferred 35 form of the invention has been shown.

In said drawing

Figure 1 is a view partly in plan and partly in section of a portion of a heading machine equipped with the improved gauge.

Figure 2 is a section through a portion of the 40 machine on line 2—2, Figure 1.

Figure 3 is an end elevation of the gauge.

Referring to the figures by characters of reference, 1 designates a portion of the body of a heading machine, the heading slide being indicated at 2 while liner plates therefor have been indicated at 3 and 4. Liner plate 4 is of sufficient thickness to allow the formation of an angular channel 5 in one face and a wedge plate 6 can be seated on the outer channeled face of the liner plate for adjusting it relative to the slide 2.

Seated snugly in channel 5 is an angular bar 7 extending from the head 8 of the gauge. This head is adapted to receive thrust from the stock S when fed into the machine and, if desired, an 45 enlargement or boss can be formed on the head,

as shown at 9, for contact with the end of the stock.

The head 8 can be made of such strength as not to bend under the pressure of stock to which it would be subjected, and as the point of contact with the stock is only slightly out of line with the bar 7 the danger of yielding or bending under pressure of the stock is further eliminated.

Any means desired can be used for adjusting the gauge. For example, a screw threaded stem 65 10 can be extended from bar 7 into a recess 11 in the machine. A nut 12 in the form of a worm gear can engage the stem 10, and is suitably held against movement axially of the threaded stem. This nut is engaged by a worm 13 on a shaft 14 70 which is located at any convenient point for actuation by a crank 15, or other suitable means.

When the stock S is fed into the machine at the opening 16 it will be guided against the stop 9 and as this stop is located only slightly out of line with bar 7 and the line of thrust is parallel with said bar, there will be no distortion of the gauge and the stock can be cut off in accurate 75 lengths by shearing and carry-over means provided for that purpose.

Obviously various other mechanisms could be used for adjusting the gauge. The structure shown and described has been presented merely as an example of one means which can be used 80

A gauge mounted as described will be out of the way of the various mechanisms constituting essential parts of automatic headers and the like and necessarily located within the feed end of the machine. Such mechanisms include means for shearing the blanks, means for carrying the blanks to the stationary die for shaping, and means for shifting or transferring the dies on the slide. These mechanisms have not been illustrated in the present case because they constitute no part of the present invention.

What is claimed is:

1. In a metal working machine of the class described a heading slide, a liner therefor, a bar adjustably seated in and projecting from one end of the liner, and a gauge head carried by the projecting portion of the bar.

2. In a metal working machine of the class described a heading slide, a liner therefor having a channel extending longitudinally in one side, a bar adjustably mounted in the channel and projecting from one end of the liner, said channel and bar being below the top level of the slide, and a gauge head on the projecting portion of the bar, there being means for guiding stock against the head along a line parallel with the bar.

3. In a metal working machine of the class described, a heading slide, a liner therefor having a longitudinal channel in one side below the top level of the slide, an angular bar within and held against rotation by the channel, said bar projecting at one end from the liner, a gauge head on the bar, means for guiding stock against the head along a line parallel with the bar, and means for adjusting the bar and head toward and from the stock guiding means. 80
5. In a metal working machine a body having a stock receiving space, a heading slide movable substantially horizontally, a stock gauge supported in the space, and means within the body at one side of the slide for adjustably supporting the gauge, said means including a liner plate for the slide. 85
10. 4. In a metal working machine a body having a stock receiving space, a heading slide, a stock gauge supported in the space, and means within the body at one side of the slide for adjustably supporting the gauge, said means including a liner plate for the slide. 90
15. 5. In a metal working machine a body having a stock receiving space, a heading slide, a stock gauge supported in the space, and means within the body at one side of the slide for adjustably supporting the gauge, said means including a liner plate for the slide. 95
20. 6. In a metal working machine a body having a stock receiving space, a heading slide, a stock gauge supported in the space, and means within the body at one side of the slide for adjustably supporting the gauge, said means including a liner plate for the slide. 100
25. 7. In a metal working machine a body, means for feeding stock thereto, a heading slide, a liner plate for the slide at one side thereof and in the body, said plate having a longitudinal channel, a member slidable in the channel in the liner plate parallel with the path of movement of the slide and below the plane of the top thereof, a head carried by the member constituting a stop gauge for stock, a plate extending along the liner plate and across the bar and channel, and means for adjusting the member longitudinally relative to the liner plate. 105
